HOWARD LYON, OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

INVERTED INCANDESCENT LAMP.

1,172,617.

Specification of Letters Patent.

Patented Feb. 22, 1916.

Application filed May 24, 1913. Serial No. 769,619.

To all whom it may concern:

Be it known that I, HOWARD LYON, a citizen of the United States, residing at Gloucester City, Camden county, New Jersey, have invented a new and useful Improvement in Inverted Incandescent Lamps, of which the following is a full, clear, and exact description, reference being had to the accompanying drawings, forming part 10 of this specification, in which—

Figure 1 is a side elevation, partly in section, showing one form of my invention as applied to a chandelier; Fig. 2 is an enlarged vertical section of the burner and 15 supply tube; and Fig. 3 is a vertical sectional view taken at right angles in Fig. 2, showing in detail the preferred form of raceway which I employ.

My invention relates to incandescent gas 20 lamps, and is designed, first, to provide a chandelier having a plurality of inverted incandescent burners supplied from a common mixing tube, which is sufficiently removed from the heat of the burners to give 25 the desired results; second, to improve the actuating connection for the control valve to the mixer, as well as the control valve for the gas; and, third, to provide an inverted incandescent gas lamp which can be turned 30 down without carbonizing the mantle.

In the drawings, referring to the form of Figs. 1 and 2, 2 represents a depending gas supply pipe, the lower end of which is screwed into a valve chamber 3, which in 35 turn is screwed into a small casting 4 having communicating side passageways 5 and 6 leading the gas to a vertically extending pipe 7, which carries the gas down to a hollow fitting 8 having an upwardly extending jet opening 9 and needle valve 10. The needle valve stem extends downwardly 40 through the lower part of the fitting, and may be adjusted by a handle 11 against the spiral spring 12. I have shown the stem of the fitting 8 as provided with an ornamental ring 13 with lock nut or washer 14. Above 45 the needle valve fitting, and separated therefrom by arms 15 of a connecting ferrule or sleeve 16, which may be screwed to the fitting 8, is the mixer tube 17. Within this tube 50 is placed a liner or raceway 18, which extends to the lower end of the mixer tube and has a cylindrical bore 19 for the major portion of its length, this cylindrical bore merging 55 into a flaring or diverging bore portion 20.

This liner tube and mixer discharge into a tube 21, which leads the gas into the main cavity of the casting 4, whence it divides and passes through the side pipes 22 to the inverted gas burners 23 shown in Fig. 1. 60 The valve casing 29 contains the usual control valve whose projecting stem is provided with lever arms 24, from which depend the rods 25 extending through holes in the lower shell 26 and provided with the usual 65 chains or flexible connections 27. From above the valve the pilot light tubes shown at 28 may be led to the incandescent burners in the usual manner. The lower part 26 of the shell, together with its upper part 29 70 surrounds and incloses the valve, and preferably the mixer tube and needle valve fitting as well as the supply tube 7 for the gas, thus giving a neat and ornamental appearance.

In Fig. 3 I show in detail the preferred form of liner or raceway for the mixing tube, which I have found by long experimentation will give such a perfect mixture, especially in connection with further diffusion before reaching the burner, that the burners may be turned down and still give a blue Bunsen flame such as will not carbonize the mantles. I have discovered that if the gas and air are perfectly mixed by 85 proper shape, length and size of liner, or inner bore of the mixing tube, the mixture may then be taken to substantially any distance or in any direction, and will give an efficient blue flame even when turned down. 90

In the ordinary inverted burners, if the flame is turned down a yellow tinge appears in the flame which will cause the carbonizing of the mantles. This I overcome by my peculiar and novel arrangement and shape of 95 the raceway for the mixer tube. I will now give an example of this tube, which operates to give the improved result with 3 to 10 cubic feet of gas per hour. In this case I use a straight liner tube 30, shown in Fig. 100 3, of about two inches long from the point from the level *a* to the level *b*. Beginning at the entrance for gas and air, and extending for about 1-1/4 inches, I make the inner bore of this tube cylindrical and of about 105 19/64 of an inch diameter. At the end of the 1-1/4 inch cylindrical bore, I then ream out the tube in tapered form for about 3/4 of an inch in length, this diverging outwardly from 5/16 to about 13/32 of an inch 110

bore at its outer end. This diverging portion is shown at 31, and from its end a straight tube portion 32 extends for preferably about six inches, and which may be of any desired diameter, preferably having a bore at least as large as 13/32 of an inch. If there is an abrupt change in the direction of flow of the gas and air current after merging from the liner tube, this fusion mixing tube may be less than six inches long. In this connection it is essential that the mixer tube be kept relatively cool by locating it out of the path of the products of combustion from the lamp. Its temperature should always be below 140 degrees C. This is one reason that the ordinary cluster inverted lamp does not permit of turning down, since the manifold, mixer tube, &c., are heated to about 250 to 300 degrees C. by the rising products of combustion. The above proportions are given for a certain volume of gas, and will be changed according to the amount of gas flowing, but in all cases the tube should be at least two inches long and should have the straight bore merging into the diverging or flaring portion. The diffusion tube through which the gas flows from the raceway of the mixing tube to the burners should have a diameter at least twice that of the combined outlets of the burners.

The advantages of my invention result from the use of the mixing tube common to several burners, and gives the same mixture and the same burning power to each lamp. By carrying the gas downwardly and then returning it upwardly before entering the branch tubes to the burners, the regulating valve for the gas is brought within easy reach of the operator. Also the control levers for the gas valve may be short so that the chains may close together, thus giving a better appearance. The ornamental shell surrounding the central fittings gives a neat and ornamental appearance, while the peculiarities of the raceway or liner tube for the mixer are found to provide for turning down the burners without carbonizing the mantles.

Certain features of my invention may be used without other features; the needle valve may be directed downwardly into a mixer tube which depends and supplies the mixture downwardly into the fitting 4, and other changes may be made without departing from my invention.

I claim:

1. A chandelier for a plurality of separated incandescent gas lamps, comprising a fitting, an upwardly extending gas supply pipe connected to said fitting and constituting the support for the chandelier, a common gas and air chamber within said fitting, a plurality of laterally extending combined gas and air supply pipes connected to the

fitting and communicating with the gas and air chamber, means for supporting a burner and glassware on the ends of each of said pipes, a mixing tube extending downwardly from the fitting and communicating with the gas and air chamber, a needle valve casing below the lower end of the mixing tube, a needle valve within said casing for controlling the supply of gas to the mixing tube, means for admitting air to the mixing tube, a gas supply tube communicating with the gas supply pipe and connected to the needle valve casing, and a valve for shutting off the supply of gas to the needle valve casing; substantially as described. 80

2. A chandelier for a plurality of separated incandescent gas lamps, comprising a fitting, an upwardly extending gas supply pipe connected to said fitting and constituting the support for the chandelier, a common gas and air chamber within said fitting, a plurality of laterally extending combined gas and air supply pipes connected to the fitting and communicating with the gas and air chamber, means for supporting a burner and glassware on the ends of each of said pipes, a mixing tube extending downwardly from the fitting and communicating with the gas and air chamber, a needle valve casing below the lower end of the mixing tube, a needle valve within said casing and controlling the supply of gas to the mixing tube, means for admitting air to the mixing tube, a gas supply tube communicating with the gas supply pipe and connected to the needle valve casing, and a valve for shutting off the supply of gas to the needle valve casing, together with a canopy inclosing the fitting, gas valve, mixing tube, needle valve chamber, and the tube connecting the needle valve chamber with the main gas supply pipe; substantially as described. 95

3. A fitting for chandelier for incandescent gas lamps having a body portion, there being a gas chamber and a gas and air chamber in said body portion in approximately the same horizontal plane, means for connecting oppositely extending inlet and outlet pipes to the gas chamber, means for connecting outlet pipes to the gas and air chamber, at right angles to the gas inlet and outlet pipes, and means for connecting a mixing tube to the gas and air chamber parallel with the gas inlet and outlet pipes; substantially as described. 110

4. A chandelier for a plurality of separated inverted incandescent gas lamps, comprising a fitting, there being a plurality of chambers within said fitting, a gas supply pipe connected to said fitting and communicating with one of said chambers, a plurality of laterally extending combined air and gas supply pipes connected to said fitting and communicating with the other chamber, a mixing tube connected to said fitting and 125

extending downwardly therefrom, said mixing tube communicating with the second chamber, a needle valve casing below the mixing tube and in line therewith, a gas supply tube connected to the needle valve casing and the fitting, said gas supply tube opening communication between the first chamber and a space within the needle valve casing, means for supplying air to the mixing tube, and a needle valve within the needle valve casing for controlling the supply of gas; substantially as described.

5. A chandelier for a plurality of separated incandescent gas lamps, comprising a fitting, an upwardly extending gas supply pipe connected to said fitting and communicating with the gas chamber in said fitting, a needle valve casing supporting below said fitting, a gas supply pipe supporting the needle valve casing connected to the fitting and adapted to supply gas from the gas

chamber in the fitting to the interior of the needle valve casing, a vertically disposed needle valve in said casing, a gas and air chamber within the fitting, a plurality of 25 gas and air supply tubes extending in radial directions from the fitting and communicating with the gas and air chamber, and a downwardly extending mixing tube communicating with said chamber extending to 30 a point slightly above the needle valve casing, said mixing tube extending parallel with the gas supply pipe connecting the gas chamber and the fitting with the needle valve casing; substantially as described. 35

In testimony whereof, I have hereunto set my hand.

HOWARD LYON.
